UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,247,690.

Specification of Letters Patent. Patented Nov. 27, 1917.

Application filed April 28, 1911. Serial No. 623,904.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

My invention relates to electric switches.

In this application I shall describe one form in which it is applied to a push-button flush switch, but my invention is in no 15 wise limited to this specific form and may assume various other forms and may be used in various other relations.

In switches of the type known as flush switches which are adapted to be set in a 20 wall so that the front casing of the switch lies flush with the surface of the wall, it is highly desirable to provide a switch construction which is adapted to break the electric circuit with great rapidity so that the 25 sparking between the contacts where the circuit is broken is reduced to the minimum. Further on account of the limited space which such switches are often required to occupy it is highly desirable to provide a 30 switch mechanism in which the contact parts are only required to move a short distance in order to disrupt the arc and for the entire switch mechanism to be of a very compact construction. Further it is 35 highly desirable to provide a switch mechanism which is exceedingly strong and reliable and composed of a small number of parts which will withstand long wear in service.

40 One object of my invention is to provide an improved electric switch adapted to break an electric circuit with a quick snap action even when actuated by a relatively slowly moving part.

45 A further object of my invention is to provide an improved electric switch adapted to break circuit with a quick snap action in which the amount of movement of the contact members is very small so that the 50 switch may be very compactly assembled.

A further object of my invention is to provide an improved electric switch which is simple of construction, reliable, and adapted to withstand long wear in service.

55 In order to illustrate the principle of my

invention I have shown in the accompanying drawings one form which it may assume in practice. My invention is not however limited to the specific form thereof illustrated in the accompanying drawings. 60

In these drawings:

Figure 1 shows a side elevation of this form of my improved switch.

Fig. 2 shows a sectional view of the same.

Fig. 3 shows a top plan view of the same. 65

Fig. 4 shows a partial longitudinal sectional view on line 4-4 of Fig. 3.

Fig. 5 shows a sectional view on line 5-5 of Fig. 1.

In these figures I have illustrated a switch 70 mechanism mounted upon an insulating base 1, which includes a movable contact carrying member 2 adapted to be reciprocated upon vertically disposed shafts 3 fixed to the base 1 on opposite sides of the 75 same, when one of two cam-carrying reciprocable push-buttons 4 and 5 is reciprocated upon posts 6 and 7 suitably fixed to the base on opposite sides of the movable contact carrying member 2. 80

The movable contact carrying member 2 is made of insulating material and preferably has a substantially rectangular cross section having square ends 8. The edges of this member 2 between the ends 8 are 85 beveled as at 9 so as to form inclined surfaces on the sides and tops of the same separated by narrow flat surfaces parallel with the side surfaces of the square ends. In a preferred form this member 2 is provided with a vertically extending perforation on each side which is centrally located and passes through the flat upper and lower surfaces of the beveled portion of the contact carrying member at points approximately the same distance apart from the middle line of this beveled portion and on opposite sides of the same. In each of these perforations is mounted a sleeve 10 which extends beyond the upper and lower surfaces of the contact carrying member as shown in Fig. 4. These sleeves are adapted to fit over the vertical shafts 3 and slide upon the same. In a preferred form these sleeves extend about the same distance above the 100 upper surface of the movable contact carrying member that they extend below the lower surface of the same. In a preferred form two steel balls 11 are seated at points approximately opposite the shafts 3 in the 105

upper surface of the movable contact carrying member that they extend below the lower surface of the same. In a preferred form two steel balls 11 are seated at points approximately opposite the shafts 3 in the 110

flat side of the left hand beveled portion of the movable contact carrying member 2, while two steel balls 12 are similarly located on the opposite side of the contact carrying member. (See Figs. 2, 4 and 5.) If desired, suitable recesses 4^a and 5^a may be formed in the upper beveled portions of the movable contact carrying member 2, between the balls 11 and between the balls 12 to permit the free movement of the push buttons 4 and 5.

The function of this movable contact carrying member is to open and close the contacts of the switch. In the construction shown in this application, I have illustrated this member as adapted to break both sides of an electrical circuit. The movable contacts are carried on the outer surface of the rectangular ends 8 of the movable contact carrying member and consist of oppositely extending sheet contacts 13 suitably fixed as by screws 14 or any other desirable means, to the outer ends 8 of this member. In a preferred form, the outer surface of each of these rectangular ends 8 is provided with a pair of vertically extending slots 15, insulated from each other, into which the inner ends of the contacts 13 are fitted, and may be adjusted if desired. The line connections for these contacts 13 are made through suitable binding posts 17 suitably fixed to the base at opposite sides of the same, and include two sets of stationary contacts 18 electrically connected to the binding posts, and two intermediate substantially U-shaped contact members 16 located between the stationary contacts 18 and insulated from said contacts 18 by the base 1. When the movable contact carrying member 2, carrying the contacts 13, is moved to circuit closing position, the circuit is simultaneously made at four points at each side of the line, and when the movable contact carrying member 2 moves upward, the circuit is broken simultaneously at these four points on each side of the line and the arc is divided between these points. In order to illustrate this more clearly, let us assume that the switch mechanism shown in Fig. 1 is in the down position, that is, in the circuit closing position. The path of the current through the contacts would then be as follows; assuming that the current enters through one of the binding posts 17: Through the binding post 17 to the left hand stationary contact 18, up through this contact to the left hand movable contact 13, across this movable contact 13 to the left hand arm of the U-shaped intermediate stationary contact 19, through the body of this contact and up through its right hand arm, to the right hand movable contact 13, through this movable contact 13 to the right hand stationary contact 18 and down through this contact to the right hand bind-

ing post 17. Thus the current will flow in series through the stationary and movable contacts of the switch and when the circuit is broken on the upward movement of the movable contact carrying member 2, it will be broken simultaneously at four points on each side of the line, that is, at the tops of the two arms of the intermediate insulating contacts 19 and at the tops of the stationary contacts 18 so that when the arc which would normally be formed between a single pair of contacts would be divided up between the four points, and be reduced to one fourth the length which it would otherwise have. This construction I find exceedingly advantageous since by dividing up the arc formed between the contacts on each side of the line into these four parts I find that the sparking at the contacts is very greatly reduced so that the life and efficiency of the contact members is very greatly increased, and that the switch may be of a very compact construction since the amount which the movable contacts have to move in order to completely disrupt the arc is only one fourth of that which they would have to move if the arc was only broken at one point. Further, by increasing the number of points at which the circuit is broken the lengths of the arcs and the amount of necessary movement of the contact parts to disrupt the same may obviously be reduced to any desired degree.

The movable contact carrying member 2 is adapted to reciprocate upon the shafts 3 upon the vertical movement of the push buttons 4 and 5 on the vertical posts 6 and 7 fixed to the base on opposite sides of the contact member 2. In a preferred form these push buttons 4 and 5 are composed of insulating material and are guided in their movement by an upper plate 20 having perforations 21 through which the push buttons 4 and 5 may be reciprocated. This plate 20 is preferably supported by vertical standards 22 suitably fixed to the opposite ends of the base 1 at points in alignment with the posts 6 and 7 upon which the push buttons are reciprocated. The push buttons 4 and 5 are preferably provided with vertically extending recesses in their lower surfaces in which are fitted sleeves 23 and 24 adapted to receive the upper ends of the posts 6 and 7 and to be reciprocated thereon. Each of these sleeves 23 and 24 is preferably provided with a collar 25 located at about the middle of the same which is adapted to have its upper surface bear against the lower surface of its push button. Upon the lower end of each of these sleeves 23 and 24 is carried a pair of oppositely extending cam members 26 and 27. The two cam members 26 are revolvably mounted upon the sleeves 23, while the two cam members 27 are revolvably mounted 130

upon the sleeves 24. In a preferred form these cam members 26 and 27 are each provided at their ends with inwardly extending arms 28 and 29 having perforations in 5 their free ends through which the sleeves 23 and 24 are passed. In a preferred form the arms 28 are set slightly farther apart than the arms 29 and inclose the same. The cams 26 and 27 are preferably formed of 10 stamped metal and their cam surfaces are of the shape indicated in Fig. 2. The cam surfaces of the two cams on the opposite sides of the sleeve 23 are each of a similar conformation while the cam surfaces of 15 each of the two cams on the opposite sides of the sleeve 24 are also of a similar conformation. As shown in this figure, the cam 26 is provided with a cam surface having oppositely inclined sides which converge 20 toward the center and are provided with knobs or projections 30 at their ends. The cams 27 are provided with cam surfaces which are of the same general construction as the cams 26, but whose active 25 surface is the opposite of that of the cam 26. Consequently while the cams 26 have somewhat the conformation of a valley having two diverging slopes, the cam 27 has somewhat the conformation of a hill having two slopes converging at the crest. As 30 in the case of the cams 26 the ends of the slopes of the cam 27 are provided with projections 31, but in this case the projections are oppositely disposed to those on 35 the cams 26. Further it is to be noted that the two slanting sides of the cams 27 meet at a sharper edge than do the slanting sides of the cams 26.

The function of these cams 26 and 27 is 40 to bear against the balls 11 and 12 set in the opposite sides of the beveled portion of the movable contact member 2 so that when the cams are reciprocated by the movement of the push buttons 4 and 5 this member 45 will be moved vertically on the shafts 3 to change the circuit connections of the switch with a quick snap action. This resilient movement is furnished by helical springs 32 and 33 which encircle the sleeves 23 and 24 50 at points between the arms 29 of one of the cam members, and whose opposite ends are brought out in back of the cams as shown at 34 and 35 in Fig. 5. The normal action of these springs is to cause the cams to 55 bear against the balls 11 and 12 and throw the cams slightly forward and inward toward each other. In order to throw one of the push buttons and the cams carried therewith on the sleeves, to the up position when 60 the other push button and its cams are pushed downward and at the same time give a positive movement to the movable contact carrying member 2 as well as the snap movement imparted to this member 2 by the 65 springs 32 and 33, I have provided a rocking

member or plate 36 pivoted to the base 1 on a short center pin 37. This plate has bifurcated ends 38 which pass around the lower parts of the posts 6 and 7 at points below the sleeves 23 and 24, and are adapted 70 to engage washers 39 encircling the shafts and force these washers upward to raise one of the sets of cams and one push button when the other set of cams and the other push button is lowered, so that a positive 75 action is supplied to move one set of parts up when the other set is pushed downward.

I will now describe the operation of a switch constructed in accordance with the drawings. Let us assume that the parts 80 are in the position shown in Fig. 1, with the circuit open. When in this position the balls 11 on the left hand side of the movable contact carrying member 2, rest at the bottom of the valley cams 26 and the balls 12 85 on the opposite sides of the member 2 rest against the upper projections 31 on the hill cams 27. As the push button 4 is lowered, the cams 26 will be thrown backward about the sleeve 23 as a pivot, due to the engagement of their upper surfaces with the balls 11 and the cams 26 will be forced downward past the balls 11. The cams 27 on the other hand, however, will be thrown backward about the sleeve 24 as a pivot, due to 90 the engagement of their upper surfaces with the balls 12 and these cams will be forced past the balls 12. The effect of this movement will be to put the movable contact carrying member 2 under pressure on opposite sides. This pressure will continue until the balls 12 pass over the crests of the hill cams 27 when it will be suddenly relieved and the cams 27 will pass above the balls 12, and be free to be swung about their 95 axis to their normal position by their helical spring 33. Since the balls 12 have passed over the crests of the cams 27 the movable contact carrying member 2 will then be free to move downward and will be impelled in 100 that direction by the lower slopes of the hill cams 27 as these cams are swung inward by their spring. Further at this time the cams 26 are exerting a downward pressure on the balls 11 and when the movable contact carrying member 2 is freed the spring 32 of these 105 cams 26 throws the cams inward so that the faces of the same are pressed against the balls 11 to cause the movable contact carrying member 2 to move downward. Thus 110 after the balls 12 have passed over the slopes of the hill cams 27 a downward pressure is exerted on both the balls 12 and the balls 11 which results in a downward movement of the member 2 with a positive quick snap 115 action. When it is desired to break the circuit the operation which has just been described is reversed and the other push button 5 is pressed downward to cause the hill cams 27 to move downward and the valley 120 125 130

- 4
- cams 26 and the push button 4 to move upward. In each of these movements there is the same positive snap action of the switch mechanism, and the same quick break at the switch contacts, the balls 12 traveling the entire length of the hill cam 27 during each operation while the balls 11 engaging the valley cams 26 travel alternately from the bottom or center portion of these valley cams 26 to one end of the same and then back to the center portion of the cams ready to be moved toward the opposite end of the cams and back to the center of the same on the next operation.
- 15 By my improved construction the length of the arc formed between the contacts and the necessary amount of movement of the movable contact member to disrupt the same may be reduced to any desired degree so that the switch contacts are maintained at their maximum efficiency for a great length of time and the switch may be very compactly assembled. Further due to the snap switch mechanism which I have employed the circuit is broken very rapidly and with a positive, quick, snap action which also tends to reduce the sparking and occurs no matter how slowly the operating members for the switch mechanism are actuated so
- 20 that the snap action of the switch may not be defeated by a slow movement of the operating members. Further due to the action of the rocking plate beneath the push buttons each push button and its cam mechanism is thrown to its proper position by a positive action when the position of the other push button and cam mechanism is changed so that the parts are always in a position to be operated.
- 25 It is to be understood that the foregoing description refers to the typical embodiment of the invention disclosed in the drawing and that in practice modifications of structure may be employed without departure from the scope of the appended claims.
- 30 What I claim as new and desire to secure by Letters Patent is:—
1. In an electric switch, in combination, a reciprocable operated member having contacts associated therewith, an operating member, a cam on one of said members bearing against the other and tending throughout movement of said operating member to shift said operated member to an opposite extreme position, a spring under the control of said cam adapted to have energy stored therein by the action of said cam and to coöperate with said cam to shift said operated member and means associated with said operating member to hold said operated member during storage of energy in said spring and to release said operated member for shifting thereof under the influence of said spring and cam.
- 35 2. In an electric switch, in combination, a reciprocable operated member having contacts associated therewith, an operating member, a cam on one of said members bearing against the other and tending throughout movement of said operating member to move said operated member to an opposite extreme position, a second cam associated with one of said members and bearing against the other to hold said operated member against movement during a limited initial movement of said operating member and to then release the former and a spring associated with one of said members adapted to have energy stored therein by the action of one of said cams while said operating member is held against movement and to contact with one of said cams to move said operated member when released.
- 40 3. In an electric switch, in combination, a reciprocable operated member having contacts associated therewith, a reciprocable operating member, a concave cam on one of said members bearing against the other and tending throughout movement of said operating member to move said operated member in a corresponding direction for selective circuit changing movement of the latter, a convex cam associated with one of said members and bearing against the other to restrain and release said operated member in different positions of said operating member and a spring coacting with said cams to effect movement of said operated member with a snap action.
- 45 4. In an electric switch, in combination, a reciprocable operated member having contacts associated therewith, an operating member, a cam on one of said members bearing against the other and tending throughout movement of said operating member to shift said operated member to an opposite extreme position, a spring under the control of said cam adapted to have energy stored therein by the action of said cam and to coöperate with said cam to shift said operated member and means associated with said operating member to hold said operated member during storage of energy in said spring and to release said operated member for shifting thereof under the influence of said spring and cam.
- 50 5. In an electric switch, in combination, a reciprocable operated member having contacts associated therewith, a reciprocable operating member, a concave cam on one of said members bearing against the other and tending throughout movement of said operating member to move said operated member in a corresponding direction for selective circuit changing movement of the latter, a convex cam associated with one of said members and bearing against the other to restrain and release said operated member in different positions of said operating member and a spring coacting with said cams to effect movement of said operated member with a snap action.
- 55 6. In an electric switch, in combination, a reciprocable operated member having contacts associated therewith, an operating member, a cam on one of said members bearing against the other and tending throughout movement of said operating member to shift said operated member to an opposite extreme position, a spring under the control of said cam adapted to have energy stored therein by the action of said cam and to coöperate with said cam to shift said operated member and means associated with said operating member to hold said operated member during storage of energy in said spring and to release said operated member for shifting thereof under the influence of said spring and cam.
- 60 7. In an electric switch, in combination, a reciprocable operated member having contacts associated therewith, an operating member, a cam on one of said members bearing against the other and tending throughout movement of said operating member to move said operated member to an opposite extreme position, a second cam associated with one of said members and bearing against the other to hold said operated member against movement during a limited initial movement of said operating member and to then release the former and a spring associated with one of said members adapted to have energy stored therein by the action of one of said cams while said operating member is held against movement and to contact with one of said cams to move said operated member when released.
- 65 8. In an electric switch, in combination, a reciprocable operated member having contacts associated therewith, an operating member, a cam on one of said members bearing against the other and tending throughout movement of said operating member to shift said operated member to an opposite extreme position, a spring under the control of said cam adapted to have energy stored therein by the action of said cam and to coöperate with said cam to shift said operated member and means associated with said operating member to hold said operated member during storage of energy in said spring and to release said operated member for shifting thereof under the influence of said spring and cam.

reciprocable operated and operating members, contacts associated with said operated member, a spring to receive and store energy, a cam on one of said members bearing against the other and tending throughout movement of said operating member to move said operated member in the direction of its ultimate movement and means associated with and controlled by said members to direct the action of said cam for storage of energy in said spring during a predetermined initial movement of said operating member in either direction.

7. In an electric switch, in combination, a reciprocable operated member having associated contacts, a pair of push button operating members therefor interlocked to move in opposite directions, means to receive and store energy upon movement of said operating members for imparting accelerated movement to said operated member, a plurality of inclined surfaces on said operating members and engaging parts on said operated member riding in a single direction over a plurality of said surfaces and back and forth over either of said surfaces upon movement of said operating member to effect said accelerated movement of said operated member through the medium of said means.

8. In an electric flush switch, in combination, a reciprocable operated member having associated contacts, a pair of push button operating members interlocked to reciprocate in opposite directions, means to receive and store energy upon movement of said operating members for imparting an accelerated movement to said operated member in either direction, a plurality of inclined surfaces on said operating members and engaging parts on said operated member riding in one direction over a plurality of said surfaces and back and forth over either of two others of said surfaces during relative movement of said members to selectively effect accelerated movement of said operated member in accordance with the direction of movement of said operating member.

9. In an electric switch, in combination, a reciprocable operated member having associated contacts, an operating member, connecting means between said members to exert counterbalancing pressures on said operated member during initial movement of said operating member to thereby hold the former against movement and to thereafter relieve one of said pressures to release said operated member and a spring coacting with said connecting means to move said operated member with a snap action when released.

10. In an electric flush switch, in combination, a reciprocable operated member having associated contacts, a pair of push button operating members therefor interlocked to reciprocate in opposite directions, a pair of

cams on one of said push buttons engaging said operated member for effecting selective movement thereof, a pair of convex cams on the other push button engaging said operated member for temporarily restraining the same, and means associated with said cams for receiving and storing energy upon movement thereof relative to said operated member.

11. In an electric flush switch, in combination, a reciprocable operated member having associated contacts, a pair of push button operating members therefor interlocked to reciprocate in opposite directions, a pair of cams on one of said push buttons engaging said operated member for effecting selective movement thereof, a pair of convex cams on the other push button engaging said operated member for temporarily restraining the same, and means associated with said cams for receiving and storing energy upon movement thereof relative to said operated member and to expend such energy for imparting accelerated movement to said operated member after cessation of the restraint thereon by said convex cams.

12. In an electric flush switch, in combination, a pair of spaced push button operating members interlocked to reciprocate in opposite directions, a reciprocable operated member having associated contacts and disposed between said push buttons, means associated with said members to receive and store energy upon movement of said push buttons for imparting a subsequent acceleration to said operated member in a circuit changing direction, a concave cam movable with one of said push buttons and engaging said operated member to determine the direction of movement of the latter in accordance with the direction of movement of said push button, and a convex cam on the other of said push buttons engaging said operated member to time the acceleration of the latter, said cams co-operating during initial movement of said push buttons to effect a storage of energy in said energy-storing means.

13. An electric switch provided with a reciprocable operated member having associated contacts, reciprocable cams engaging said operated member and interlocked to move simultaneously in opposite directions and a spring, said cams coacting to store energy in said spring while holding said operated member stationary and said spring after receiving a storage of energy coacting with said cams to move said operated member.

14. A flush switch provided with contact actuating means comprising a movable member, convex and concave cams in resilient engagement with said movable member and push buttons for actuating said cams and interlocked to simultaneously move said

cams in opposite directions upon operation of either of the same.

15. A flush switch provided with contact operating means comprising a reciprocating member, a pair of push buttons, a plurality of cams actuated by one of said push buttons and engaging one side of said member, a plurality of cams actuated by the other push button and engaging the opposite side of said member, certain of said cams being convex and others concave, means for holding said cams and said members in resilient engagement and means operatively connecting said push buttons to move the same with their respective cams in opposite directions upon operation of either of the same.

16. In a flush switch, in combination, a sliding member, contacts carried thereby, guides for said sliding member, a pair of push buttons, a pair of spaced cams connected to each push button, said pair of cams being in resilient engagement with said sliding member on opposite sides thereof, certain of said cams being concave

and others convex, and means connecting said push buttons to cause the same to move with their cams in opposite directions upon operation of either.

17. In a flush switch, in combination, a sliding member, contacts carried thereby, a pair of push buttons, a pair of spaced cams connected to each push button, said pair of cams being in resilient engagement with said sliding member upon opposite sides thereof, certain of said cams being concave and others convex, means connecting said push buttons to cause the same to move with their cams in opposite directions upon operation of either, and terminal contacts and intermediate contacts engaged by said contacts on said sliding member.

In witness whereof, I have hereunto subscribed my name in the presence of two witnesses.

CHARLES J. KLEIN.
